Filed Apr. 1, 1960, Ser. No. 59,994

Term of patent 7 years

(Cl. 55—1)

FIG. 1

FIG. 2

FIG. 3

FIG. 4

FIG. 5

FIG. 1 is a view in elevation showing one side of a feeding hopper, showing my new design;

FIG. 2 is a view in elevation corresponding to FIG. 1 showing the opposite side thereof;

FIG. 3 is a view in end elevation as seen from the right side of FIG. 1.

FIG. 4 is a view in end elevation as seen from the left side of FIG. 1; and

FIG. 5 is a view in bottom plan.

The design for the feeding hopper disclosed is characterized by the shape of the base portion below the hopper feeder element, the sides of which portions slope

inwardly then downwardly, and the arrangement of the members on said base portion.

I claim:

The ornamental design for a feeding hopper, as shown and described.
